(No Model.)

C. A. SHERMAN.
Circular Saw Guide.

No. 233,563.

Patented Oct. 19, 1880.

Fig. 3.

UNITED STATES PATENT OFFICE.

CLARENCE A. SHERMAN, OF PLOVER, WISCONSIN.

CIRCULAR-SAW GUIDE.

SPECIFICATION forming part of Letters Patent No. 233,563, dated October 19, 1880.

Application filed May 10, 1880. (No model.)

To all whom it may concern:

Be it known that I, CLARENCE A. SHERMAN, of Plover, in the county of Portage and State of Wisconsin, have invented a new and Improved Circular-Saw Guide, of which the following is a specification.

The object of this invention is to provide a device for preventing the lateral vibration of a circular saw while running.

10 The invention consists of a pair of laterally-adjustable guide-arms and guides fixed on an adjustable bar that passes laterally through a centrally-mortised reversible sliding block, which block and its attachments are held in place by means of a cam-operated bar.

Figure 1 is a plan of the device. Fig. 2 is a longitudinal elevation of the same, partly in section. Fig. 3 is a cross-section on line x x , Fig. 1.

20 Similar letters of reference indicate corresponding parts.

In the drawings, A represents the bed-plate, which is secured to the saw "husk" or frame by four screws, a a . B is the sliding block, 25 provided on upper and lower sides with V-shaped grooves b b and resting on the V-shaped ways c of the bed-plate A, so that it may slide longitudinally on said bed-plate A without danger of lateral displacement. Said 30 block B is provided with a mortise, d , extending entirely through it from side to side, and is provided also on either face with rectangular grooves f running centrally across it. Through this mortise d of the block B the bar

35 C is inserted, having in one end a screw, C' , on which is a wheel, D, provided with an internally-threaded hub, as shown at b' , by means of which wheel D the bar C is adjusted. This wheel D is held in place by the bearing

40 D', that is secured to the end of the block B, and has its lower edge engaged in the annular groove b'' of the hub of said wheel D. On the opposite end of this bar C are fixed the two guide-arms E E, which guide-arms E E are

45 held in place by the set-screws h h , that enter through their ends and press against the side of the said bar C. These guide-arms E are set parallel to each other, and have their inner faces formed into semicircles, as shown at i , so

50 that when said guide-arms E E are in position

a circular opening is formed between them. The free ends of said guide-arms E have transverse mortises k formed in them, through which mortises the saw-guides F are inserted, and held adjustably in place by set-screws l . 55

The sliding block B and its attachments are held in place by the clamping-bar G, which bar G is secured at one end of the bed-plate A by a bolt, m , and extending longitudinally and centrally over the said bed-plate A and the 60 said block B, and is fitted into the upper rectangular groove, f , of the said block B, and has its other end fitted over the cam-pin n , which projects upward from the other end of the said bed-plate A, and the cam-lever H, which is 65 pivoted on the top of the cam-pin n , above the bar G, operates to hold the said bar G firmly down upon the sliding block B, so as to retain said block B in any position.

This device is designed to prevent the lateral vibration of the circular saw to make it run truly in a vertical plane, and for this purpose the guide-arms E are adjusted on either side of the saw, as indicated in dotted lines at K, and the guides F pressed against the 75 saw, as shown, and held in place by the set-screws l .

This device can be applied to a right or left handed saw-mill by reversing the block B with its attachments. 80

The wheel D, working directly upon the bar C, prevents the possibility of the said bar C or the guide-arms E E getting out of place.

Having thus described my invention, I claim as new and desire to secure by Letters Patent—

1. A circular-saw guide constructed substantially as herein shown and described, consisting of bed-plate A, sliding block B, provided with mortise d and grooves f , bar C, 90 provided with screw C' , wheel D, clamp D' , guide-arms E E, guides F F, and cam-actuated bar G, as set forth.

2. In a circular-saw guide, the combination, with the bed-plate A, provided with V-shaped ways c , of the reversible sliding block B, provided with V-shaped grooves b b , central mortise, d , and grooves f f , and clamp-bar G, substantially as herein shown and described. 95

3. In a circular-saw guide, the combination, 100

with the centrally-mortised sliding block B and bar C, of the inwardly-curved adjustable guide-arms E E, provided with adjustable guides F F, substantially as herein shown and 5 described.

4. In a circular-saw guide, the combination, with the bed-plate A, sliding block B, bolt and

pin m n, and clamping-bar G, of the cam-lever H, substantially as herein shown, and for the purpose described.

CLARENCE A. SHERMAN.
